UNITED STATES PATENT OFFICE

CARL G. OLSON, OF CHICAGO, ILLINOIS, ASSIGNOR TO SHAKEPROOF LOCK WASHER COMPANY, OF CHICAGO, ILLINOIS, A CORPORATION OF DELAWARE

SCREW LOCKING ELEMENT

Application filed July 31, 1930. Serial No. 471,973.

My invention relates generally to screw locking elements and more particularly to devices of this nature formed from a single strip of stock.

5 It is one of the objects of my invention to provide a locking element for screws and the like of improved practical construction which may be conveniently manufactured from a single piece of elongated wire stock.

10 Another object of my invention is to provide a locking element of annular construction which is formed with a plurality of adjacently positioned coils of wire stock, said coils being provided with teeth for lockingly engaging the work.

15 Still another object of my invention is to provide a locking element as above set forth comprising a plurality of coils of wire stock, said stock being of polygonal cross section and twisted so as to present a plurality of helical work engaging edges.

20 My invention also contemplates the provision of a locking element as above set forth which is equipped with a terminal section 25 adapted to receive the free extremity of a conductor.

25 These and other objects will be more apparent from the following detailed description when considered with the accompanying drawing, wherein—

30 Figure 1 is a plan view of a lock washer construction in accordance with the teachings of my invention;

35 Figure 2 is a front elevational view of Figure 1;

40 Figure 3 is a plan view of a locking element similar to Figure 1 having a radially extending terminal section formed integral therewith;

45 Figure 4 is a plan view of a modified coiled locking element which is twisted throughout its length so as to present helical locking edges;

50 Figure 5 discloses a locking element similar to Figure 4 which is equipped with a radially extending integral terminal section; and

55 Figure 6 is still another modified locking element in which the internal coil is twisted

and the external coil as well as the terminal sections are not twisted.

Referring now to the drawing more in detail, wherein I have employed like numerals to designate similar parts shown in the various figures, it will be seen that my invention contemplates the provision of a locking element which includes a single strip of wire stock which is bent into annular form so as to present a pair of nested coils or rings 10 and 12. The ring 10 is nested within the ring 12 and is connected with the ring 12 through the agency of a deflected radial section 14 which extends between the extremity 16 of the ring 10 and the extremity 18 of the ring 12. These extremities 16 and 18 are deflected outwardly in opposite directions so as to present work engaging locking edges 20. These edges are adapted to imbed themselves within the work piece when the clamping action is exerted axially of the locking element.

It will be noted that the outer periphery of the ring 10 is adjacently positioned with respect to the inner periphery of the ring 12, the space presented between these surfaces being sufficiently small so as to enable a film of tin 22, indicated by the stippling in Figure 1, to become lodged therein during the tinning operation. In this way, the tin surface serves as a binder between the coils or rings 10 and 12, thereby securing said coils against expansion when clamped between a nut and a work piece. A locking element of the type shown in Figure 1 presents a very rigid construction and provides a very effective means for preventing a nut against retrograde movement.

In Figure 4 I have disclosed a locking element similar to the device shown in Figure 1, the only difference being that the device of Figure 4 is formed from a single strip of stock which has been previously twisted so as to prevent a plurality of work engaging helical edges 24.

In my co-pending application Serial No. 472,373 filed August 1, 1930, I have shown a locking element formed with a plurality of helical edges as shown in Figure 4, but my present invention differs from the structure

set forth in said co-pending application in providing a plurality of rings or coils which have been previously twisted. It should be noted that the twist imparted to the locking 5 element of Figure 4 is such as to counteract a tendency for the rings to expand in response to the tightening action of a nut.

In Figure 3 I have shown a locking element of modified form wherein a radial terminal section 26 is formed integrally with the rings 10 and 12, the outer extremity of said terminal section being formed with an aperture 28 for receiving the free extremity of a conductor. It will be seen that the terminal section 26 is formed by extending the ring or coil 10 outwardly in a radial direction and then returning the stock so as to join the ring 12.

In Figure 5 a still further modification is shown wherein a structure similar to Figure 4 is formed with a radially extending terminal section 26. Likewise in Figure 6 a still further modification is disclosed. This construction in Figure 6 includes a ring or coil 12—A which has not been previously twisted and a nested twisted coil 10—A, both of said coils being connected by a radially extending terminal section 26.

From the foregoing, it will be seen that 30 my invention presents a very simple locking element which may be formed by merely subjecting a strip of wire stock to bending operations. The fact that the entire locking element is formed from a unitary strip of material eliminates the loss which has heretofore 35 been occasioned when locking elements, terminals and the like have been stamped from flat stock. In other words the entire portion of the wire stock is employed in forming my 40 improved locking device. Obviously numerous changes and modifications may be made in the structure without departing from the spirit and scope of my invention and, therefore, said invention should be limited only 45 on the scope of the following claim.

Having thus described my invention what I claim as new and desire to secure by Letters Patent is:

A locking element formed from a single 50 strip of wire stock including an outer annular section, an inner annular section, the outer periphery of the inner section being positioned adjacent the inner periphery of the outer annular section, work engaging teeth 55 associated with said annular sections and projecting out of the plane thereof, and binding material interposed between the adjacent annular surface of said annular sections.

In witness whereof, I have hereunto subscribed my name.

CARL G. OLSON.
